(57) **CLAIM**

The ornamental design for a deep muscle stimulator, as shown and described.

DESCRIPTION

FIG. 1 is a side perspective view of an embodiment of a deep muscle stimulator showing my new design;

FIG. 2 is a front elevational view of FIG. 1;

FIG. 3 is a rear elevational view of FIG. 1;

FIG. 4 is a right side elevational view of FIG. 1;

FIG. 5 is a left side elevational view of FIG. 1;

FIG. 6 is a top plan view of FIG. 1; and,

FIG. 7 is a bottom plan view of FIG. 1.

The broken lines are for illustrative purposes only and form no part of the claimed design.
